UNITED STATES PATENT OFFICE.

FREDERICK H. OEHlke, DECEASED, LATE OF RIDGEVILLE, OHIO, BY LAURA AUGUSTA PEASE, EXECUTRIX, OF RIDGEVILLE, OHIO, ASSIGNOR TO BERTHA M. OEHlke, OF WEST DOVER, OHIO.

FURNACE.

1,307,371.

Specification of Letters Patent. Patented June 24, 1919.

Application filed April 11, 1918. Serial No. 227,876.

To all whom it may concern:

Be it known that FREDERICK H. OEHlke, who was a citizen of the United States, and who resided at Ridgeville, in the county of 5 Lorain and State of Ohio, invented certain new and useful Improvements in Furnaces; and I, LAURA AUGUSTA PEASE, his executrix, do hereby declare the following to be a full, clear, and exact description of the invention, such as will enable others skilled in the art to which it appertains to make and use the same.

The invention relates to furnaces for heating buildings and the like, and is especially 15 adapted for use in connection with such heating systems as those in which hot water is employed to carry the heat from the furnace to the radiators or other distributing means.

20 The principal object of the invention is to increase the efficiency of furnaces of the type in which a plurality of fuels of different character is employed.

Another object of the invention is to provide 25 a furnace in which the different fuels may be used individually or together, without interference one with the other.

Another object of the invention is to provide 30 a furnace constructed of individual parts, which can readily be assembled and some of whose parts are duplicates of each other, so that the size of the furnace may be readily varied by using any suitable number of such similar parts.

35 Another object of the invention is to produce a furnace whose parts may be readily and conveniently removed and renewed.

Cheapness in construction, stability and 40 durability are other objects of the invention.

These and other objects of the invention, as well as the invention itself will be more readily understood from a description of an embodiment of the invention.

45 Figure 1 is a vertical section through an embodiment of the invention taken along the line 1—1 in Fig. 2.

Fig. 2 is a vertical section of the embodiment illustrated in the drawing taken 50 along the line 2—2 of Fig. 1.

Fig. 3 is a section taken along the line 3—3 of Fig. 1.

Fig. 4 is a section taken along the line 4—4 of Fig. 1.

55 Referring now to the drawings and to the

embodiment of the invention shown therein, at 5 is shown the frame or body part of the furnace and at 6 a top part therefor. The frame is provided with a water jacket 7, forming a water space 8 all about the side walls of the body part of the furnace, which, in the embodiment shown, is rectangular in cross section. As will be seen, the body part of the furnace is built up of a plurality of sections, here shown at 51, 52, 53 and 54. 60 Suitable means are employed for connecting these sections together, here illustrated as flanges 9 and 10, which are connected together by any suitable means, such as bolts 11. The interior walls are provided with 70 coöperating teeth 12 and flanges 13 arranged to fit together when the parts are assembled, making a sealed, water-tight joint.

A tortuous passage-way is shown at X, which consists of a flat conduit zigzagging 75 back and forth across the frame as it ascends from the bottom to the top thereof. This conduit extends clear across the furnace, as illustrated in Fig. 2, dividing the same into two passage-ways O and O', for 80 the gases, etc. The points 15 of the angles of the conduit X do not join the interior walls of the furnace, but approach only near enough to leave suitable spaces 16 through which the gases, etc., from the fire chambers 85 pass upwardly about the water inclosing parts to the top of the furnace.

The sections of the conduit X pass diagonally across the sections of the furnace between the points a and b, so that the products of combustion rising strike full against the walls of conduit X, as indicated at C, and then ascending along same, as indicated at d. The walls of X being inclined, expose a large surface to the fumes, and as 90 will be seen, fumes from both fire boxes S and R contact with X, those from S one side and those from R the other side thereof.

Openings 17, 17₁, 17₂, and 17₃ are provided in the ends of the conduit X, through 100 which such conduit is placed in communication with the water jacket. The conduit is provided with a plurality of ribs 18, which serve to strengthen the parts and to collect and convey the heat from the gases, 105 etc. to the water in the conduit.

A water feed chamber is shown at Y', which is located at about the center of the bottom of the main chamber and which likewise extends clear across the same. This 110

- feed chamber communicates with the water jacket through openings y' in the ends of the chamber. The conduit X enters the chamber through an opening 20 therein.
- 5 Means, such as pipes 21, are provided for supplying water to the chamber Y'. A distribution chamber V is shown in the top of the furnace, communicating with the conduit X through an opening 22 therein.
- 10 Means, such as pipes 222, are provided for conveying the heated water to the radiators or other distributing means which are not shown in the drawing, but which are well understood.
- 15 Hollow baffles Y are shown extending from the interior wall of the furnace into the angles between the zig-zagging parts of the conduit. These baffles communicate through openings y with the water space 8.
- 20 The bottom part or section 51 of the furnace is divided into two fire chambers by the walls of the chamber Y'. One of these chambers S is adapted for the burning of coal, wood or the like and a coal grate s is
- 25 illustrated therein.

At 30 is shown an opening normally closed by a door s' for the introduction of fuel to the chamber S, and at 31 is shown an opening normally closed by a door s_1 ,

30 through which the ashes, etc. may be withdrawn. At s_2 is shown a door controlling the supply of air to the chamber S and at s_3 and s_4 , means by which the door may be opened and closed. At T is shown the ash pit.

At R is shown another fire chamber, suitable for burning gas. An opening is provided through which entry may be had to the chamber R, normally closed by a suitable door. At r_1 , r_2 and r_3 are shown burners in the chamber R. A duct 32 is employed for supplying gas to the burners. The hot gases, etc. from the chamber S pass upwardly in the direction of the arrows, and

45 the gases from the chamber R, upwardly, following the course indicated by the other arrows. It will be seen that the hot gases, etc., from the chamber S engage one side of the tortuous passage X, both sides of the

50 baffles on one side of the furnace, illustrated by the baffle Y, and three of the walls of the water jacket part of the furnace. The hot gases, etc., from the chamber R engage the other side of the tortuous passage X,

55 the other baffle or set of baffles and three of the water-jacketed sides of the furnace. The gases, etc., from the chamber S escape through an opening 34 and those from the chamber R, through an opening 35, where

60 they are conveyed away by suitable means, such as conduits, one of which is illustrated at 36 in Fig. 2.

It will be appreciated that duplicates of the sections 53 may be inserted between the

65 sections 52 and 53 or 53 and 54, thus varying

the size of the furnace, as desired. The sections are made of suitable material, such as cast iron. Either solid, that is, non-gaseous fuel or gas may be burned, or both may be burned simultaneously. Neither can interfere with the other. The draft of the solid fuel side cannot interfere with that of the gas side, and the latter cannot be clogged with soot from the burning of solid fuel on the other side. The heat from either is

70 adapted to raise the water to a certain temperature and when both are burned, the heat from each coöperates with the other to raise the temperature of the water still higher.

75 The baffles serve the double purpose of 80 keeping the hot gases in close engagement with the walls of the tortuous passage and exposing portions of the water to the hot gases as they ascend. It will be seen that portions of the system for exposing the wa- 85 ter to the heat of the gases is common to the plurality of heating systems employed. It will be apparent that the part 53 may be omitted from the furnace and the part 54 reversed and the bottom thereof joined to 90 the top of the part 53.

These details and this embodiment have been shown to illustrate the invention. It will be apparent that many departures may be made therefrom without departing from 95 the spirit of the invention.

Claims:

1. In a furnace, the combination of a frame built up of sections, a water jacket and space for water all about the sides of the furnace, a chamber for burning solid fuel in one side of the frame, a chamber for burning gas in the other side of the frame, a chamber for water between said fuel and gas burning chambers and extending clear 100 across the furnace interior, said water chamber joining the opposite side walls of the furnace where it communicates with the water jacket, a conduit for water joining at its lower end with said water chamber and zig-zagging alternately above said fuel and gas burning chambers to the top of the furnace, said conduit extending from side to side of the interior of the furnace and joining the side walls thereof where it communicates 105 with the water jacket through openings provided through the walls of the jacket, the points of the angles of the conduit being spaced from the side walls of the interior of the furnace to permit hot gases, etc., to pass 110 therebetween, hollow baffles substantially triangular in cross section extending from the interior walls of the furnace into the angles formed by the conduit, said baffles joining with the water jacket through openings 115 provided in the end and sides thereof, a top part for the furnace, a water distribution chamber in the top part provided with an opening at which the conduit is joined to said chamber and through which it com- 120

125

130

- municates therewith, means through which water is supplied to the water chamber and means through which is is distributed from the distribution chamber.
- 5 2. In a furnace, the combination of a plurality of fire chambers, a water jacket forming a water space about said furnace, a tortuous passage for water extending from top to bottom of the furnace and from side to side thereof, a plurality of hollow baffles in the angles in said passage, the walls of the water space being provided with openings through which the passage, the baffles and the water space are placed in communication, a top part for said furnace and means through which water is introduced and withdrawn from said water space.
- 10 3. In a furnace, the combination of a main inclosing shell, an inner shell spaced therefrom, means for joining together said shells at the top and bottom to form a chamber for heating-fluid, a zigzag passageway extending vertically inside the inner shell and joined thereto at the sides, the channel in 40 said passageway communicating at the sides with said fluid chamber, said inner shell having hollow extensions on each side projecting inside the angles of the passageway but spaced therefrom to form flues for hot 50 gases, means for feeding fluid into the bottom of the passageway, and means whereby it may escape at the top thereof, a fire grate at the bottom of said shells on one side of said passageway, and a gas burner at the 55 bottom on the other side, whereby the passageway completely separates the two and forms separate paths for the products of combustion from each.
- 15 4. In a furnace, the combination of a main inclosing shell, an inner shell spaced therefrom, means for joining together said shells at the top and bottom to form a chamber for heating-fluid, a middle passageway extending vertically inside the inner shell and joined thereto at the sides, the channel in 45 said passageway communicating at the sides with said fluid chamber, said inner shell having hollow extensions on each side projecting inside the angles of the passageway but spaced therefrom to form flues for hot 50 gases, means for feeding fluid into the bottom of the passageway, and means whereby it may escape at the top thereof, a fire grate at the bottom of said shells on one side of said passageway, and a gas burner at the 55 bottom on the other side, whereby the passageway completely separates the two and forms separate paths for the products of combustion from each.
- 20
